UNITED STATES PATENT OFFICE.

ARTHUR MORLEY BROWN, OF YE KOWHAI, NGARUAWAHIA, NEW ZEALAND, ASSIGNOR TO PROVIDENCE ENGINEERING WORKS, OF PROVIDENCE, RHODE ISLAND, A CORPORATION OF RHODE ISLAND.

INTERNAL-COMBUSTION ENGINE.

No. 873,493.

Specification of Letters Patent.

Patented Dec. 10, 1907.

Application filed September 20, 1904. Serial No. 225,274.

To all whom it may concern:

Be it known that I, ARTHUR MORLEY BROWN, a subject of the King of Great Britain, residing at Ye Kowhai, Ngaruawahia, Auckland, in the Colony of New Zealand, have invented certain new and useful Improvements in Internal-Combustion Engines, of which the following is a specification.

10 This invention relates to internal combustion engines, and has for its principal object to effect the cooling of the explosive charge and to increase its weight as well as to permit of the use of a higher compressed charge 15 than usual, and hence a greater amount of power is obtained than is usually obtained from a given size of cylinder; an increased saving in working is also obtained.

Further objects attained are the cooling of 20 the circulating water supplied to the cylinder and the providing of a cool scavenging charge of air for expelling the products of combustion from the engine and providing means for starting the engine.

25 The improvements hereinafter described may be applied to internal combustion engines working on the four-stroke or Otto cycle principle or to a two-stroke cycle engine and to engines having one, two or more cylinders.

30 With the foregoing and other objects in view, the invention consists of the novel construction, combination and arrangement of parts hereinafter more specifically described 35 and illustrated in the accompanying drawings which form a part of this specification, and wherein is shown the preferred embodiment of the invention, but it is to be understood that changes, variations and modifications 40 can be resorted to which come within the scope of the claims hereunto appended.

In the drawings, wherein like reference characters denote corresponding parts throughout the several views Figure 1 represents 45 in longitudinal section, the improvements constituting my invention applied to or combined with a single cylinder horizontal internal combustion engine working on the Otto-cycle principle, Fig. 2 represents a portion of a two-stroke engine provided with two mixing chambers and Fig. 3 is a longitudinal section of a portion of an explosive engine, showing the manner of constructing the same when used in connection with this invention.

a is the engine cylinder and b is the air pump or compressor near to the said cylinder a and worked preferably from the engine. The compressed and heated air in the air-compressor b is conveyed by the pipe l to the main air-receiver and intercooler marked d, d^2 at a pressure considerably above atmospheric pressure; the air receiver proper consisting of an annular chamber indicated by the reference character d and the axial cooler denoted by the reference character d^2 . Cold water or air is made to circulate through the axial cooler d^2 in any convenient manner. By this means, the compressed and heated air supplied from the air compressor b is cooled. A compartment receptacle is provided to receive the compressed cooled air and also the combustible gas or hydrocarbon before either or all of the constituents of the explosive mixture is or are supplied to the mixing chamber c, to be hereinafter referred to. One of the compartments is termed a supplementary or expansion air receiver, and the other of the compartments a gas-receiving chamber. The compartment receptacle is termed a supplementary compartment receiver. The reference character e denotes the supplementary or expansion air-receiver, and the reference character f, the gas-receiving chamber. Into the supplementary air-receiver e, through the medium of the pipe g, the compressed cooled air in the main air-receiver d is passed and expanded and the pressure and temperature of the air thereby lowered. The air is controlled and cut off by the valve or tap g^2 .

It will be seen that the supplementary or expansion air-receiver e is surrounded by the annular chamber f to which is supplied, by means of the supply pipe h, the combustible gas or hydro-carbon which forms a constituent of the explosive mixture and which is fed to the mixing chamber c. By the passing of the heated air through the air-receiver and expander e and the gas through the chamber f surrounding it, the said air and gas are cooled before being received in the mixing or controlling chamber c of the engine. The cooled and expanded air is supplied to the mixing chamber c by the pipe k and the cooled gas by the pipe l. The annular space f in the air expanding receiver may be used for expanding and cooling the air and the inner chamber e for cooling the gas instead of the arrangement represented in the draw-

ing. The expansion receiver e, f is "lagged" or jacketed with a non-conducting material marked f^2 . The control of the supply of cooled air and gas to the mixing chamber c is had through the medium of the valves k^2 and j^2 , the former being arranged in the pipe k , and the latter in the pipe j . By the admission of the explosive charge of air and gas into the mixing chamber c it is further cooled.

The mixture of air and gas forming the charge in the chamber c is ejected from the said chamber and injected into the engine cylinder a through the valve-controlled communication c^2 during the outstroke of the piston.

For the purpose of starting the engine, the compressed air from the main air-receiver d is either conveyed direct by the pipe t , provided with a controlling valve t^2 , to the mixing chamber c and the explosive mixture under pressure is ejected from the said chamber into the combustion chamber c^3 of the engine; or preferably the explosive mixture or charge under pressure is admitted from the mixing chamber c , by a valve-controlled communication c^2 , into the combustion chamber c^3 of the engine-cylinder and ignited.

For cooling the circulating water supplied to the jacket of the engine-cylinder a and to provide a cool scavenging charge of air to the interior of the engine-cylinder for expelling the products of combustion from the said cylinder the following arrangement is used; a second compartment receptacle is provided, and one of its compartments is adapted to receive the compressed cooled air, and the other of its compartments is adapted to receive water. The manner in which the air and water are supplied to the second compartment receptacle, will be hereinafter referred to. The compartment which receives air is termed the second or supplementary air expander, and the compartment which receives the water, is termed an annular space or water-receiving chamber. The second compartment receptacle is termed a secondary or supplementary compartment receiver.

m is the circulating water tank connected with the jacket of the engine-cylinder a at its top by the return circulating water pipe s and at its bottom by the water pipe p which latter communicates with the water chamber or annular space r of the second or supplementary air expander o by which latter the scavenging charge is supplied to the engine-cylinder. The compressed air from the main air-receiver d is supplied to the axial chamber o of the second air-chamber by the pipe u controlled by the valve u^2 , a pipe q having a valve q^2 is in connection with the chamber o for conveying the scavenging charge of air to the interior of the engine-cylinder. The annular chamber or jacket r of the second

air-chamber o is in communication at one end by means of the valve-controlled pipe n with the water-tank m and at the other end by the pipe p , passing to the bottom of the water-jacket of the engine-cylinder. The second expansive air-receiver is "lagged" or jacketed with a non-conducting material r^2 .

The cooling water may circulate through the axial chamber o and the air be cooled and expanded by circulating about the annular chamber r instead of employing the arrangement of parts represented.

In either of the ways described the circulating water for the engine-cylinder is cooled and a cool scavenging charge of air provided.

The cycle of operations is as follows:—On the first outstroke of the piston the valve controlling the communication between the mixing chamber c and the engine-cylinder a is opened, thus allowing the explosive mixture to be injected into the combustion chamber of the said cylinder a . On the return stroke of the piston, the charge is compressed into the combustion chamber at the back of the piston. On the second outstroke of the piston, the charge is ignited and expansion takes place to the end of the stroke, then the exhaust valve opens, allowing the products of combustion to escape from the cylinder. On the second return stroke of the piston, the valve controlling the cool air scavenging charge passing through the chamber o is opened, thereby allowing the said cool air to thoroughly expel the products of combustion from the cylinder. The said cool air entering the cylinder also cools the latter before a fresh charge of explosive mixture is admitted to the cylinder.

The timing of the several operations is effected by mechanism which is of the ordinary kind and constitutes no part of my invention.

In carrying my invention into effect for an engine working on the two-stroke principle in which one cylinder gives an impulse every revolution, I take a single-cylinder horizontal engine having an ordinary trunk piston 1 (Fig. 3) but in place of the usual exhaust valve, the cylinder 2 is provided with exhaust ports 3 all round the circumference as is common to some class of engines, so that when the piston has completed its full stroke, the exhaust ports are uncovered sufficiently to allow a free exhaust for the products of combustion. With this kind of engine is combined the air compressor, air-receiver and cooling arrangements hereinbefore described and illustrated in Fig. 1 with respect to an engine working on the Otto-cycle principle.

The cycle of operations of the two-stroke engine is as follows: On the outstroke of the piston, the compressed charge contained in the combustion chamber at the back of the piston, is ignited, thus impelling the piston and allowing expansion to take place to the end of the stroke when the exhaust ports are

uncovered and the burned products escape freely; the valve controlling the cool air scavenging charge is then opened and the burned products expelled thoroughly from the cylinder and the cylinder at the same time cooled before a fresh charge of explosive mixture is admitted to the cylinder. During the return stroke of the piston, the valve of the mixing chamber is opened and a fresh charge of explosive mixture is injected into the cylinder which is compressed into the combustion chamber at the back of the piston during the return stroke of the piston ready to be ignited as before described.

15 In applying my invention to two stroke or two cycle engine working either single or double acting which is double acting, like an ordinary steam-engine, where one cylinder gives two impulses every revolution, I take a 20 single-cylinder horizontal engine and in place of the usual exhaust valves, the cylinder is provided with exhaust ports all round the circumference as before described the air compressor, air-receiver and cooling arrangements hereinbefore described and illustrated in Fig. 1 being employed excepting that I use two mixing chambers as represented in Fig. 2 and marked, respectively, *c* and *c'*, a mixing chamber being arranged at each end of the cylinder *a* instead of using a single mixing chamber as before described. In this case the two mixing chambers are in communication with independent combustion chambers. In the arrangement Fig. 2, the connecting 35 pipes are marked with the same letters of reference as corresponding parts in Fig. 1, but their positions are somewhat modified. In the said Fig. 2, the two mixing chambers are connected to the compressed air supply 40 by the pipe *k*, and the gas supply by the pipe *j*. The compressed air pipe for starting the engine is marked *t* and the pipe for supplying the cool air scavenging charge connected to the two ends of the cylinder is marked *q*.

45 The cycle of operations is exactly the same as in the engine giving an impulse every revolution except that the cycle occurs twice every revolution.

I do not limit myself to the number of 50 mixing chambers used in connection with my invention. For example in employing an engine having two cylinders, working on the two-stroke principle double-acting as last described, I use four mixing chambers in connection with four independent combustion chambers; and as hereinbefore stated my invention is applicable to engines working on the four-stroke or two-stroke principle and to engines having one, two, three or more 55 cylinders.

Having thus fully described my invention, what I claim as new and desire to secure by Letters Patent, is.

60 1. Attachments for internal combustion engines for the purpose set forth embodying

a cooler for compressed air, a supplementary receiver provided with compartments, means for establishing communication between one of the compartments of the receiver and the cooler and between the other of the compartments of the receiver and a combustible gas or hydrocarbon supply, a mixing and controlling chamber, and means for establishing communication between the combustion chamber of the engine and one of said compartments of the receiver.

65 2. Attachments for internal combustion engines comprising means for introducing a cooled blast of scavenging air into the combustion chamber of the engine, said means embodying a receiver for compressed air, a water supply communicating with the jacket of the combustion chamber of the engine and a receiver provided with compartments, one of said compartments communicating at one 70 end with said cooler and at its other end with the combustion chamber of the engine, and the other of said compartments communicating at one end with the water jacket, and at its other end with the water supply.

75 3. Attachments for internal combustion engines for the purpose set forth comprising a cooler for compressed air, a combined mixing and controlling chamber for the explosive mixture communicating with the combustion chamber of the engine, and means for supplying compressed air from said cooler to said combined mixing and controlling chamber.

80 4. Attachments for internal combustion engines, embodying a compressed air supply, a compartment receiver provided with compartments, a valve-feed pipe between one of the compartments of said receiver and said compressed air supply, a pipe communicating with the other of said compartments of said supplementary compartment receiver and with a combustible gas or hydrocarbon supply, and means for establishing communication between the compartments of said receiver and the combustion chamber of an engine.

85 5. Attachments for internal combustion engines, comprising the combination with a compressed air supply, of a supplementary compartment receiver, a valved feed pipe between one of the compartments of said receiver and said compressed-air supply, a pipe communicating with the other of said compartments of said supplementary compartment receiver and with a combustible gas or hydrocarbon supply, a combined mixing and controlling chamber, a valved pipe for establishing communication between said mixing chamber and the combustion chamber of the 90 engine, a valved pipe for establishing communication between the air-receiving compartment of said supplementary compartment receiver and said mixing chamber, and a valved pipe for establishing communica-

95 100 105 110 115 120 125 130

tion between the other compartment of said supplementary compartment receiver and the said mixing chamber.

6. Attachments for internal combustion engines, comprising means for introducing a cooled blast of scavenging air into the combustion chamber of the engine, said means comprising a supplementary compartment receiver, means for establishing communication between one of the compartments of the receiver and a compressed-air supply, means for establishing communication between the other compartment of said receiver and a water supply, means for carrying off the water from the water compartment of the receiver, and a valved pipe for establishing communication between the air-receiving compartment of said receiver and the combustion chamber of the engine.
7. Attachments for internal combustion engines, comprising means for introducing a cooled blast of scavenging air into the combustion chamber of the engine, said means comprising a water supply communicating with the jacket of the combustion chamber of the engine, a supplementary compartment receiver having an air and a water-receiving compartment, a valved pipe for establishing communication between the water-receiving compartment and said water supply, a valved pipe for establishing communication between said air-receiving compartment and

a compressed-air supply, a pipe for establishing communication between the water-receiving compartment and the jacket of the combustion chamber of the engine, and a valved pipe for establishing communication between the air-receiving compartment and the combustion chamber of the engine.

8. Attachments for internal combustion engines, comprising a compartment-receiver having one of its compartments adapted to receive compressed air and the other of the compartments a combustible gas or hydrocarbon, means for establishing communication between said air-receiving chamber and a compressed-air supply, means for establishing communication between said combustible gas or hydrocarbon-receiving chamber and a source of supply, a combined mixing and controlling chamber, means for establishing communication between said controlling chamber and the combustion chamber of an engine, and means for establishing communication between the compartments of said receiver and said combined mixing and controlling chamber.

In testimony whereof I have hereunto set my hand in presence of two subscribing witnesses.

ARTHUR MORLEY BROWN.
